UNITED STATES PATENT OFFICE.

WILLIAM D. KYLE, OF MILWAUKEE, WISCONSIN, ASSIGNOR TO LINE MATERIAL COMPANY, OF SOUTH MILWAUKEE, WISCONSIN, A CORPORATION OF WISCONSIN.

LINE-CONDUCTOR INSULATOR.

Application filed September 19, 1924. Serial No. 738,635.

The invention relates to insulators, more particularly adapted for attaching conductor wires to buildings or other supports.

An object of the invention is to provide an insulator having a detachable base member for retaining an attaching screw therein in keyed or driving relation to obviate the necessity for permanently fastening the screw in place on the insulator.

Another object of the invention is to provide an insulator of this type in which the parts of the insulator are connected by a pair of bolts extending longitudinally through them and straddling a transverse wire-receiving opening.

The invention further consists in the several features hereinafter set forth and more particularly defined by claims at the conclusion hereof.

In the accompanying drawings: Fig. 1 is a side view of an insulator embodying the invention secured to a support;

Fig. 2 is a front end view thereof;

Fig. 3 is a rear end view thereof;

Fig. 4 is a longitudinal sectional view taken on the line 4—4 of Fig. 2;

Fig. 5 is a front end view of the base member at the line 5—5 of Fig. 4; and

Fig. 6 is a front end view of a modified form of insulator body.

In these drawings, 10 indicates an insulator body of porcelain, a hardened plastic, or other suitable insulating material, having a transverse wire-receiving opening 11, an annular wire-receiving groove 12, preferably but not necessarily in the plane of the opening 11, and a wire-receiving groove 13 extending around the head 14 of the insulator body in an axial plane and merging with the opening 11 at opposite sides.

A base member 15 of insulating material abuts against the rear end of the insulator body 10 and is connected thereto by a pair of bolts 16 passing longitudinally through the insulator body and base member through openings 17 and 18, respectively, the openings 17 being disposed on either side of the transverse opening 11. In that form of insulator shown in Figs. 1 to 5 the heads 19

of the bolts are of polygonal shape, preferably square, to enter polygonal recesses 20 in the head 14 at the outer ends of the openings 17 in order to retain the bolts against rotation. The other ends of the bolts are

disposed in recesses 21 in the base portion 55 where they receive nuts 22 for clamping the insulator body and base member together. The bolts may also be locked against rotation in other ways, as by having polygonal shanks 60 disposed in similar openings, or the nuts 22 may be held against rotation while the bolts are turned.

A threaded attaching member 23 passes through an opening 24 in the base member 15 and is provided with a head 25 which is 65 preferably polygonal for disposition in a similar recess 26 formed in the base member to prevent relative rotation of the attaching member with respect to the insulator, but the head may enter the insulator body, if 70 desired, for the same purpose. The attaching screw is in the form of a lag screw, as shown in Figs. 1 and 4, when used on a wooden support, and in the form of a machine screw when entering a metal support. 75 The attaching screw is preferably centrally disposed on the insulator, as shown.

In assembling these parts the attaching screw 23 is inserted through the opening 24 in the base member with its head fitting 80 within the polygonal recess 26. The bolts are then passed through the openings 17 and 18 in the insulator body and base member, respectively, and the nuts 22 are threaded onto the bolts within the recesses 21 to clamp 85 the insulator body and base member together. The attaching screw 23 is thereby held against rotation and removal from the insulator so that the screw may be turned into a support 27 by turning the insulator. 90 For this purpose a turning tool may be inserted through the transverse opening 11 or a wrench may be applied to the polygonal surfaces 28 or 29 on the insulator body and base member, respectively, to bring the base 95 member into abutment with the support.

The polygonal surfaces are omitted in the insulator body 10' shown in Fig. 6, and the bolt head-receiving recesses 20' therein need not be polygonal when slotted head bolts are 100 used, as they may be held against rotation by a screw driver, or they may be turned by the screw driver while the nuts are held stationary.

While the base member 15 is preferably 105 of insulating material to avoid staining the walls of a house to which the device is attached, it will be apparent that a metal base

may be employed instead. With either form of base the longitudinally extending bolts serve to reinforce the insulator.

The line wire to be supported is run through the opening 11 with a tie wire in the groove 13 or 12, but opposite arrangements may be employed. In some cases the line wire may be tied on the insulator by twisting it to form a loop after passing it through the opening 11 and around the groove 13 or the groove 12 on one side of the insulator, this type of fastening being used particularly when the line wire changes direction at the insulator. The loop engaging the insulator is then disposed in the continuous seat formed by these grooves merging with the opening 11 so that the wire is held therein against displacement. The annular groove 12 may also be employed to receive both the line wire and the tie wire.

The device obviates the necessity for cementing or otherwise permanently securing the attaching screw into place and is readily assembled and mounted on a support.

25 What I claim as new and desire to secure by Letters Patent is:

1. An insulator comprising an insulator body having a wire-receiving portion, a base member, a threaded attaching member substantially centrally thereof extending loosely through said base member and having a non-circular head engageable therewith, and clamping means for securing said base member to said insulator body to retain the head of said attaching member between them, said attaching member being held within the insulator against relative rotation, whereby the attaching member may be screwed into a support by rotation of the insulator.

2. An insulator comprising an insulator body having a wire-receiving portion, a base member, a threaded attaching member extending loosely through said base member but having non-circular portions held therein against relative rotation to permit driving of said attaching member by the insulator, and metal reinforcing and clamping means for securing said base member to said insulator body to retain said attaching member against longitudinal removal.

3. An insulator comprising an insulator body having a wire-receiving portion, a base member, a threaded attaching member extending loosely through said base member and having a polygonal head fitting therein to prevent its relative rotation and to permit driving of said attaching member by the insulator and metal clamping means for securing said base member to said insulator body to retain the head of said attaching member in said base member.

4. An insulator comprising an insulator body having a wire-receiving portion, a base member, a threaded attaching member extending loosely through said base member substantially coaxially therein and having a head engageable with the forward end of said base member, and means for securing said base member to said insulator body for retaining the head of said attaching screw between them, said screw being held therein against relative rotation and the insulator having polygonal surfaces for receiving a turning tool to screw the attaching member into a support.

5. An insulator comprising an insulator body having a wire-receiving portion, a polygonal tool-receiving base member, a threaded attaching member extending loosely through said base member but held therein against relative rotation to permit driving by said base member, and means for securing said base member to said insulator body to retain said attaching member against removal.

6. An insulator comprising an insulator body having a wire-receiving portion, a base member, an attaching screw extending loosely through said base member substantially centrally therein and having a head engageable during driving with the rearward end of said base member, and means for securing said base member to said insulator body for retaining the head of said attaching screw between them, said screw having non-circular portions held loosely within the base member against relative rotation and the insulator having tool-receiving abutments for screwing said attaching screw into a support.

In testimony whereof, I affix my signature.

WILLIAM D. KYLE.

CERTIFICATE OF CORRECTION.

Patent No. 1,663,011.

Granted March 20, 1928, to

WILLIAM D. KYLE.

It is hereby certified that error appears in the printed specification of the above numbered patent requiring correction as follows: Page 2, line 30, claim 1, strike out the words "substantially centrally thereof" and insert the same to follow after the word member, line 31; and that the said Letters Patent should be read with this correction therein that the same may conform to the record of the case in the Patent Office.

Signed and sealed this 17th day of April, A. D. 1928.

M. J. Moore,
Acting Commissioner of Patents.
